UNITED STATES PATENT OFFICE.

CHARLES W. ARMBRUST, OF CRYSTAL LAKE, ILLINOIS, ASSIGNOR OF ONE-FOURTH TO
SYDNEY STEIN, OF CHICAGO, ILLINOIS.

BRAKE-SHOE.

1,019,583.

Specification of Letters Patent.

Patented Mar. 5, 1912.

Application filed March 25, 1911. Serial No. 616,801.

To all whom it may concern:

Be it known that I, CHARLES W. ARMBRUST, a citizen of the United States, residing at Crystal Lake, in the county of McHenry and State of Illinois, have invented certain new and useful Improvements in Brake-Shoes, of which the following is a specification.

This invention relates to brake shoes of the general type or class known as interlocking shoes wherein the back and face of the shoes are provided with interlocking means so that a partially worn shoe can be detached from the brake head and applied to the wearing face of a new shoe, thus enabling the partially worn shoe to be completely used up.

Various modifications of interlocking shoes have been devised prior to my present invention, but so far as I am aware, the interlocking feature has been confined entirely to plain shoes and has not been applied to what are commonly known as flange shoes or driver shoes. It is well known to those familiar with the art that the driver shoes, that is, the shoes which are used on the locomotive to engage with the driver wheels, are usually and preferably of the flange type, although flange shoes are sometimes employed in connection with the cars, as well.

This invention aims to provide interlocking shoes of the flange type so that two similar flange shoes may be interlockingly engaged, the locking provisions being so constructed that the shoes will be locked together entirely across their width. In order to accomplish this result the flange portion as well as the body portion of each shoe is equipped with locking provisions.

The invention will perhaps be best understood from the following description when taken in connection with the accompanying drawings illustrating one preferred form of my invention and throughout the various views, of which like reference characters refer to similar parts.

Referring to the drawings—Figure 1 is a side elevation of a brake shoe embodying my invention. Fig. 2 is a view showing the back of the shoe. Fig. 3 is a view showing the face of the shoe. Fig. 4 is a trans-

verse sectional view on the line 4—4 of Figs. 1 and 2. Fig. 5 is a transverse sectional view on the line 5—5 of Fig. 1. Fig. 6 is a side elevation of a modified form of my invention. Fig. 7 is a back view thereof. Fig. 8 is a face view thereof; and Fig. 9 is an elevation looking at the flange side of still another modified form of my invention.

Referring to the drawings it will be apparent that the brake shoe proper comprises a body portion 6, the face of which is adapted to bear against the tread of the wheel to which it is applied and a flange 65 portion 7 located at one side of the body portion and integral therewith and arranged to be positioned over the flange of the wheel. A groove 8 extending longitudinally of the flange portion is provided to receive the 70 wheel flange. A locking stud 9 is formed centrally of the body portion of the shoe and upon the back thereof and the walls of this stud are undercut so that a detachable fastening lug 10 may be engaged therewith, 75 as shown in Figs. 1 and 4. The fastening lug is attached to the locking stud preferably by moving the lug longitudinally of the shoe, but it will be obvious that it might be attached by moving it transversely of 80 the shoe, if preferred; in that event, however, a slightly different form of lug would be required in which the key-slot is disposed at right angles to the undercut walls of the lug. The back of the shoe, shown in Figs. 85 1 and 5, is also provided preferably near its ends with locking lugs 12 which extend transversely of the shoe, the walls of these lugs being undercut for locking engagement with similarly shaped recesses 13 on the face 90 of a similar shoe. A locking recess 14 is also formed centrally of the face of the body portion, this recess being adapted to receive and locking engage with the locking stud 9 of a similar shoe. It will be noted that the recess 14 extends only partially across the face of the body portion the outer end of the recess being closed. The end wall of the recess is undercut as well as the side walls to insure a firm locking engagement 95 between the recess and its companion locking stud.

Upon the face of the flange portion of the shoe and outside the flange groove 8 I have

provided locking lugs 15 spaced from the ends of the shoe and from each other, the ends of these lugs being undercut, as shown, for locking engagement with the undercut 5 end walls of recesses 16 provided on the back of the flange portion of a similar shoe. The face of the flange portion between and at each end of the locking lugs is preferably removed to nearly the depth of the groove 8 so that the face of the flange portion at these points will fit over the back of the flange portion of a similar shoe and will permit relative lateral movement between the shoes so that they may be interlocked.

15 Shoes made in accordance with the disclosure of Figs. 1 and 5 may be interlocked by inserting the locking lugs 12 and the locking stud 9 into the open ends of the locking recesses 13 and 14 and then moving 20 the shoes transversely relatively to each other until the stud reaches the closed end of the recess 14. This movement will cause the lugs 15 on the flange portion to enter the recesses 16 and lock the flanges of the 25 shoes together. It will be obvious from Figs. 4 and 5 that lateral displacement of the lower shoe to the left, viewing these figures, is prevented by engagement of the side walls of the interlocked flanges as well as by the locking stud 9 which abuts against the end wall of the recess 14. When the shoes are in working position the wheel flange is relied upon to prevent lateral displacement of the lower shoe in the opposite direction.

30 35 In the modifications disclosed in Figs. 6, 7 and 8, the body portion 6 is provided with the locking stud 9, as previously described, but instead of having merely a locking lug at each end of the shoe I have provided locking lugs 16 disposed intermediate the locking stud 9 and the end locking lugs 17. The back of the flange is provided with four locking recesses 18 having undercut walls for locking engagement with the locking 40 lugs 19 disposed on the face of a similar shoe. The recesses 20 which alternate with the locking lugs 19 are adapted to fit over elevations 21 alternating with the locking recesses 18 on the back of the flange. The 45 centrally disposed locking recess 14 is arranged to engage with the locking stud 9 and the transverse locking recesses 22 and 23 are adapted to coöperate with the locking lugs 16 and 17 to lock the shoes together. 50 55 While I have shown in this modification the back of the flange as provided with elevations at the ends and the face provided with corresponding depressions or recesses at the ends, it will be obvious that this arrangement may be reversed, if desired, and it will also be obvious that the number of the recesses and elevations arranged in alternation across the shoe may be increased or diminished, as desired.

60 65 In the modification disclosed in Fig. 9 the

flange is provided with the same number of elevations 24 and depressions 25, as are shown in Figs. 6, 7 and 8, but the side walls of the elevations and depressions, instead of being undercut to establish an interlocking 7 relation between the flanges, are arranged parallel with each other and approximately at right angles to the longitudinal axis of the shoe. This construction permits the elevations and depressions on the back and face 7 of similar shoes to interfit or slide into each other so as to form a continuous flange without interlocking, the locking lugs and recesses on the bodies of the shoes being depended upon entirely to retain the shoes in 8 interlocked relation.

It is believed that the invention and many of its advantageous features will be understood from the foregoing without further description and it will be obvious that various minor mechanical changes in the size, formation and arrangement of the various parts may be resorted to without departing from the spirit or sacrificing any of the material advantages of the invention. 9

I claim:

1. A brake shoe comprising a body portion and an elevated flange portion, the back and face of said body and flange portions being provided with interlocking means 9 whereby similarly shaped shoes may be locked together.

2. A brake shoe comprising a body portion and a flange portion, the back of the body portion and the face of the flange portion being provided with locking lugs and the face of the body portion and the back of the flange portion being provided with recesses adapted to interlockingly engage with the locking lugs on a similar shoe. 10

3. An interlocking brake shoe comprising a body portion and a flange portion, the back of said body portion being provided with locking lugs spaced apart and the back of said flange portion being provided with locking recesses disposed intermediate said locking lugs and the face of the shoe being provided with locking recesses and locking lugs adapted to interlockingly engage with the lugs and recesses on the back of a similar shoe. 11

4. An interlocking brake shoe comprising a body portion and a flange portion, locking lugs formed on the face of said flange portion and recesses formed on the back thereof 12 and adapted to interlockingly engage with the locking lugs on a similar shoe.

5. An interlocking brake shoe comprising a body portion and a flange portion, the back and face of said flange portion being 12 provided with means for locking the flanges of similar shoes together and the back and face of the body portion being provided with means for locking the body portions of similar shoes together. 13

6. An interlocking brake shoe comprising a body portion and a flange portion, said body portion being provided with a centrally disposed locking stud and a plurality of locking lugs and the flange portion being provided with a plurality of locking lugs, the faces of the body and flange portions opposite the locking lugs being provided with locking recesses adapted to interlockingly engage with the lugs of a similar shoe. 10
7. An interlocking brake shoe comprising a body portion and a flange portion, the back of the body portion being provided with a centrally disposed locking stud adapted to be detachably engaged by a removable attaching lug, the back of the flange portion being provided with undercut locking recesses; the face of the body portion having a locking recess closed at one end, the walls of the recess being adapted to engage with a locking stud on a similar shoe and the face of the flange having locking lugs adapted to engage in the locking recesses on the flange of a similar shoe 20 whereby the shoes are locked together. 25
8. A brake shoe comprising a body portion and a flange portion, said flange portion being grooved longitudinally on its face and having a plurality of locking lugs disposed outside said groove and the face of the body portion being provided with transversely extending locking recesses adapted to interlockingly engage with locking lugs on the back of a similar shoe. 30
- 35 9. An interlocking brake shoe comprising a body portion and a flange portion, said flange portion being provided near its outer edge with locking lugs and having a wheel flange receiving groove extending longitudinally of the shoe between said lugs and said body portion, the back of the flange being provided with locking recesses adapted to interlockingly engage with said lugs on a similar shoe and the body portion being provided on its back and face with locking means whereby the body portions of similar shoes may be locked together. 40
- 45 10. A brake shoe comprising a body portion and an elevated flange portion, said flange portion being equipped with provisions for interlocking engagement with the flange portion of a similar shoe. 50
- 55 11. An interlocking brake shoe comprising a body portion and a flange portion, said flange portion being provided with alternating elevations and depressions adapted to interfit with corresponding elevations and depressions on the flange of a similar shoe. 60
- 65 12. An interlocking brake shoe comprising a body portion and a flange portion, said body portion being provided on its back with locking lugs and on its face with locking recesses and said flange portion being provided on its back and face with alter-
- nately arranged elevations and depressions adapted to engage with the elevations and depressions on a similar shoe. 70
13. An interlocking brake shoe comprising a body portion and a flange portion, said body and flange portions being provided with lugs and recesses adapted to coöperate with the lugs and recesses on the body and flange portions of a similar shoe to lock said shoes together. 75
14. A brake shoe comprising a body portion and a flange portion having its back elevated above the back of the body portion, said shoe being provided with means whereby similarly shaped shoes may be locked together upon relative transverse movement thereof. 80
15. A brake shoe comprising a body portion, a flange portion having its back elevated above the back of said body portion, said body portion being provided with means whereby the bodies of similarly shaped shoes may be locked together upon relative transverse movement thereof. 85
16. A brake shoe comprising a body portion and a flange portion, the back of said flange portion being elevated above the back of said body portion and said flange portion being provided with means whereby the flanges of similarly shaped shoes may be locked together. 90
17. A brake shoe comprising a body portion and a flange portion, the back of said flange portion being elevated above the back of said body portion, and said body and flange portions being provided with means whereby similarly shaped shoes may be locked together. 100
18. A brake shoe comprising a body portion and a flange portion, the face of said flange portion being depressed relatively to the face of said body portion, and means whereby similarly shaped shoes may be locked together upon relative transverse movement thereof. 105
- 110 19. A brake shoe comprising a body portion and a flange portion, the face of said flange portion being depressed relatively to the face of the body portion, said body portion and flange portion having provisions whereby similarly shaped shoes may be locked together. 115
20. A brake shoe comprising a body portion and a flange portion, the back of said flange portion being elevated above the back of the body portion, said shoe having provisions for interlocking engagement with a similarly shaped shoe upon relatively transverse movement of said shoe. 120
- 125 21. A brake shoe comprising a body portion and a flange portion, the face of said flange portion being depressed relatively to the face of said body portion, said shoe being equipped with means whereby a similarly shaped shoe may be locked thereto 130

upon transverse movement of one of said shoes relatively to the other.

22. A brake shoe comprising a body portion and a flange portion elevated relatively to said body portion, said body and flange portions having provisions whereby a similarly shaped shoe may be interlockingly en-

gaged therewith upon movement of one of the shoes transversely relatively to the other.

CHARLES W. ARMBRUST.
